UNITED STATES PATENT OFFICE.

WILLIAM B. COULTER, OF BRISTOL, CONNECTICUT.

RELIEF-VALVE FOR STEAM-CYLINDERS.

SPECIFICATION forming part of Letters Patent No. 289,071, dated November 27, 1883.

Application filed April 17, 1883. (No model.)

To all whom it may concern:

Be it known that I, WILLIAM B. COULTER, of Bristol, in the county of Hartford and State of Connecticut, have invented certain new and useful Improvements in Automatic Relief-Valves; and I do hereby declare the following to be a full, clear, and exact description of the invention, such as will enable others skilled in the art to which it appertains to make and use the same.

My invention relates to an improvement in relief-valves, the object of the same being to provide a device of this character which shall be adapted to adjust itself to the pressure of any engine without the aid of springs or adjusting-screws, and which shall work automatically to relieve an engine-cylinder of any undue pressure that may be exerted on the same from the presence of water or cramping of the exhaust in any way; and with these ends in view my invention consists in certain novel features of construction and combinations of parts, as will be hereinafter described, and pointed out in the claims.

The accompanying drawing is a sectional view of my improvement.

A represents the steam-pipe, connected to the boiler of an engine or to the main feed-pipe, which conveys the live steam to the cylinder, and leads into the chest B of the valve. The casing E of this chest B is firmly secured to the main casing or barrel C by a nut, m, provided with the lip n. To the upper end of the valve-stem D, and registering with the steam-chest B, is secured, by a pin, a, and screw o, the sleeve F, which acts as a valve, and which rests on the seat b. To the lower end of the main casing C is firmly secured the lower section, G, which latter is provided with a discharge-pipe, H, and also pipes I K, leading, respectively, to the front and rear ends of the cylinder.

R represents a bushing, preferably made of brass, and fitting snugly within the main casing C. This casing is made with a shoulder, i, on which is seated the upper portion of the bushing R, the lower portion of the latter projecting below the casing, and provided with a nut, p, which impinges against the lower side 50 of the casing and keeps the said bushing down

tightly on the shoulder i. In this bushing reciprocates the main valve-stem D, and which also affords a seat for the upper valve, F.

S represents a drip-passage from the steam-chest B, formed partly in the bushing R and partly in the main casing C, to allow of the escape of the condensed water in the steam-chest B. At the outer end of this passage, and within the casing C, is placed a petcock (not shown) to prevent the escape of steam. 60

The section G is divided into two parts by the partition L. A second partition, O, subdivides the lower portion of the section G into two independent parts, said section G being thus divided into three compartments. 65 Through the partition L, and on either side of the partition O, is a passage, M, adapted to be opened and closed by the valve D.

Having described the construction of my improved device, I will now set forth its operation.

The pipe A allows the free passage of steam from the boiler to the chest B. The pipes I K allow the passage of the pressure in the cylinder into the chambers of the section G, 75 which remains there while the engine is in motion. When the pressure of the steam in the boiler exceeds that in the cylinder, the pressure on the upper end of the valve D will be greater than on the lower end, and thus 80 keep the valve down tightly on the partition L and close the openings M; but when from any cause the pressure in the cylinder is in excess, the greater pressure on the lower end of the valve will force the latter up and allow the 85 escape of the water or steam through the openings M and through the discharge H. When the pressure is decreased in the chest, it will again force the valve D down and close the 90 openings M.

It will be seen that but one device is necessary for an engine, and when the lower end of the valve D is forced up it opens both openings M, and relieves one end of the cylinder of the steam-pressure and the other end of the 95 water-pressure.

My improvement is simple in construction, is efficient in use, and can be applied to any engine at a slight initial cost.

Having fully described my invention, what 100

I claim as new, and desire to secure by Letters Patent, is—

1. A relief-valve provided at one end with a pipe connecting with the boiler or main feed-pipe, and at the other end with two pipes connecting with both ends of the cylinder, and mechanism whereby the valve automatically relieves the cylinder of any excess of pressure, substantially as set forth.
10. 2. The combination, with a valve-casing inclosing a valve-stem having a valve at each end, of a chamber connected with the boiler, and adapted to receive one of the valves of the stem, and a chamber having a discharge-outlet and opening into two compartments respectively connected with opposite ends of the cylinder, the openings between the chamber and compartments being simultaneously opened or closed by the other valve on the said 20 valve-stem, substantially as set forth.
15. 3. The combination, with a valve-casing provided with an outlet for condensed steam and inclosing a valve-stem having a valve at each end, of a chamber connected with the boiler and arranged to receive one of the valves of the stem, and a chamber having a discharge-outlet, the lower portion of the said chamber being divided into two independent compartments by a partition, said compartments be-

ing respectively connected with the front and rear ends of the cylinder, and also having openings leading into the upper portion of said chamber, said openings being adapted to be opened and closed by the other valve on the stem, substantially as set forth.

4. The combination, with a valve-casing, C, provided with opening S, shoulder i, and bushing R, said casing inclosing a valve-stem provided with a valve at each end, of a chamber connected to the boiler and arranged to receive one of the valves of the stem, and a chamber provided with an outlet and the partitions O and L, the latter provided with the openings M, adapted to be opened and closed by the other valve of the stem, the partition O dividing the lower portion of the chamber into two independent compartments respectively connected with the front and rear ends of the cylinder, all of the above parts combined and adapted to operate as described.

In testimony whereof I have signed this specification in the presence of two subscribing witnesses.

WILLIAM B. COULTER.
